D 17665

UNITED STATES PATENT OFFICE.

WARREN BARNHART, OF CHICAGO, ILLINOIS, ASSIGNOR TO ARTHUR M.
AND ALSON E. BARNHART, OF SAME PLACE.

DESIGN FOR A FONT OF PRINTING-TYPE.

SPECIFICATION forming part of Design No. 17,665, dated August 30, 1887.

Application filed February 1, 1887. Serial No. 226,194. Term of patent 7 years.

To all whom it may concern:

Be it known that I, WARREN BARNHART, a citizen of the United States, residing in the city of Chicago, county of Cook, and State of Illinois, have invented and produced a new and original Design for a Font of Printing-Typcs, of which the following is a specification, reference being had to the accompanying typographical illustration, forming a part hereof.

10 The general character of the design is grotesque, somewhat condensed, of medium weight; and it consists of capitals, lower-case, figures, points, character &, one logotype, and \$.

The distinguishing features of the design 15 are—

First. A sickle-shaped stroke for such curves as the right-hand element of h. This is seen in lower-case h, k, m, n. The frequency of these letters in ordinary composition makes 20 this feature much more noticeable in a page of matter composed of this font than in the mere alphabet.

Second. The separation of curved from straight strokes in lower-case letters having 25 both curved and straight elements. This is seen in a, b, d, g, h, m, n, p, q, r, u, y.

Third. The use of one oblique and one horizontal ceriph at the top of capitals which have 30 more than one line terminating at the top. This is seen in capitals H, U, V, W, and X.

Fourth. The use of a peculiar terminal resembling a ceriph at the lower end, several vertical and oblique strokes produced by swelling the line to a slight spur on one side and cutting it away below the spur in a long 35 sweeping concave curve, making the element end in a fine point in the line of the side opposite that from which the spur projects. This is seen in lower-case f, q, and y and in capitals A, B, F, H, K, M, N, P, R, T, V, W, 40 and X.

I claim—

The design for a font of type herein shown and described, which is a medium weight, slightly grotesque, marked by the sickle- 45 shaped curve for the final stroke of some lower-case letters, as h, m, n, the separation of straight from curved strokes in lower-case letters, as a, b, d, g, h, m, n, p, q, u, y, the oblique ceriph in proximity to a horizontal ceriph at the top of 50 some capitals, H, U, V, W, X, and the fine tapering terminal merging in a lateral spur at the lower end of some stems, as capitals B, F, H, K, M, N, P, R, T, V, W, and X and lower-case f, q, y, substantially as illustrated and described. 55

WARREN BARNHART.
